UNITED STATES PATENT OFFICE.

ALBERT KÖNIG, OF JENA, GERMANY, ASSIGNOR TO THE FIRM CARL ZEISS, OF JENA, GERMANY.

REDUCING TACHEOMETER.

Application filed January 26, 1924. Serial No. 688,883.

To all whom it may concern:

Be it known that I, ALBERT KÖNIG, a citizen of Germany, and residing at Jena, Germany, have invented a new and useful Reducing Tacheometer (for which I have filed 5 an application in Germany February 2, 1923), of which the following is a specification.

The present invention relates to a reducing 10 tacheometer containing a telescope which, in order to produce double images, is provided with a bisected lens system whose both parts with an alteration of the angle of elevation of the telescope automatically undergo a displacement relatively 15 to each other. Such a tacheometer has, e. g., been described in the French patent specification 514,536.

The present invention strives for providing 20 for the automatic reduction, i. e., for the automatic indication of the distance projected into the horizontal plane of a sighting point not being on a level with the station of the tacheometer, the simplest possible 25 mechanisms. A particularly simplified device serving this purpose is obtained if the two parts of the lens system (provided that the optical axis between the lens system and the horizontal axis is unbroken) be dis- 30 placedably disposed relatively to each other and parallelly to the horizontal axis of the telescope system (if therefore a horizontal staff be supposed), and if furthermore at least one of the two parts of the lens system 35 be in contact with a plane surface, which with alterations of the angle of elevation brings about the relative displacement of both parts.

Another suitable device is obtained if at 40 least one of the two parts of the lens system coacts instead of with a plane surface with a gearing constructed after the manner of a crank guide.

The invention is not only applicable to 45 tacheometers of that kind with which a fixed measuring angle is used, i. e., whereby to different distances correspond different sections of the staff, but also to tacheometers of the other kind with which the measuring 50 angle for horizontal sighting lines is variable in such a way that to all distances corresponds one and the same section of the staff.

If provision be made for the above men- 55 tioned plane surface, a particularly sim-

plified constructional form is obtained if it be parallel to the vertical axis of the telescope and intersects the horizontal axis of the telescope at an angle deviating from 90°. Besides, by rendering this angle adjustable, there results a simplified arrangement for a tacheometer of that kind with which to all distances corresponds one and the same section of the staff. In tacheometers of the other kind with which to different 60 distances correspond different sections of the staff, one attains by rendering the said angle adjustable a simplified arrangement which affords, if the distance of the double images deviates from a whole multiple of the image 65 of the unit of the graduation of the staff (if therefore two divisions of the staff do not coincide with each other), an exact reading of that fraction of the distance which corresponds to the fraction of this unit ad- 70 justed at any one time. However, it is also possible to attain an arrangement serving the same purpose without rendering the said angle adjustable. It consists in this that in front of the upper or the lower half of 75 the objective there is disposed a plane-parallel plate which is rotatable about an axis perpendicular to the horizontal axis and the optical axis of the objective.

When using the aforesaid plane surface 80 another constructional form is attained by applying this surface on a slide which is so coupled to the telescope as to participate in rotations about the horizontal axis and which slide, on the telescope being rotated 85 about the horizontal axis, undergoes a displacement perpendicular to the horizontal axis by means of a gearing constructed after the manner of a crank guide.

In order that the distances read off will 90 be directly the distances from the vertical axis of the telescope, it is advisable to select the distances of the telescope objective and of the bisected lens system from the horizontal axis and the focal length of the objective 95 in such a manner that a virtual image of the bisected lens system is produced by the objective at the locus of the horizontal axis.

In the annexed drawing Figs. 1 and 2 100 show in a plan elevation and in a side elevation respectively a reducing tacheometer according to the present invention, Fig. 1 being a section on line 1—1 of Fig. 2 and Fig. 2 a section on the line 2—2 of Fig. 1. Fig. 105 110

3 shows in a side elevation a second constructional example, Figs. 4 and 5 show in a plan elevation and in a side elevation respectively a third constructional example, Fig. 4 being a section on the line 4-4 of Fig. 5 and Fig. 5 a section on the line 5-5 of Fig. 4. Figs. 6 and 7 illustrate the essential parts of a fourth constructional example in a front elevation and a plan elevation respectively, Fig. 7 being a section on the line 7-7 of Fig. 6.

In the example shown in Figs. 1 and 2 there correspond to different distances different sections of the staff. On a carrying body *a* is supported rotatably about an axis X-X (which forms the vertical axis of the instrument) a carrier *b*, containing a fork *b*¹. In the latter there is rotatably supported a telescope *c* in such a way that its axis of rotation Y-Y (the horizontal axis of the instrument) perpendicularly intersects the vertical axis X-X. The telescope *c* contains an objective *c*¹, an ocular *c*², a glass plate *c*³ provided with crossed threads and two semi-lenses *c*⁴ and *c*⁵, whose plane boundary surfaces are parallel to the horizontal axis Y-Y. The distances of the objective *c*¹ and of the semi-lenses *c*⁴ and *c*⁵ from the horizontal axis Y-Y are so chosen and the objective has such a focal length that the semi-lenses are virtually imaged by the objective into the locus of the horizontal axis. Each of the semi-lenses is provided with two pivots *c*⁶ and *c*⁷ which are guided in the casing of the telescope *c*; the axes of the pivots *c*⁷ lie in the plane containing the horizontal axis and the objective axis. Each pivot *c*⁷ is provided at its free end with a ball *c*⁸, laying against a plane surface of a plate *d*, whereby a spring *c*⁹, disposed between each semi-lens and the telescope casing and wound round the apertaining pivot *c*⁶, causes a continuous contact between the ball and the plate. Each plate *d* is so disposed on the fork *b*¹ that its plane surface *d*⁰ is parallel to the vertical axis X-X and embraces with the horizontal axis Y-Y an angle which would be 90° if the semi-lenses would be in their middle position, i. e. in such a position that their axes would coincide with the objective axis *c*¹. Whilst the plate *d* corresponding to the semi-lens *c*⁴ is fixed on the fork *b*¹ by means of a set-screw *d*¹, the plate *d* corresponding to the semi-lens *c*⁵ is supported on the fork *b*¹ with the aid of a shaft *d*², which can be rotated by means of a milled head *d*³, rotatably about the axis Z-Z of this shaft. The axis Z-Z is parallel to the vertical axis X-X and intersects the horizontal axis Y-Y. On the shaft *d*² is fixed a toothed wheel *d*⁴ which engages in a toothed wheel *e* supported on the carrier *b* rotatably about the vertical axis X-X. This toothed wheel *e* is rigidly connected to a drum *e*¹, whose

axis coincides with the axis X-X and which coacts with an index *b*², parallel to its axis and fixed on the carrier *b*. Upon the drum *e*¹ is on the one hand traced a number of circular lines *e*² which are numbered according to distances *E*₁, *E*₂ . . . , and on the other hand a number of curves *e*³, numbered according to additional distances ΔE ₁, ΔE ₂ . . . . The above described arrangement is destined, in those cases in which the distance apart of the double images, produced by the displacement of the semi-lenses out of their middle position, of the staff sighted at deviates from a whole multiple of the image of the unit of the graduation of the staff, to afford a more exact reading than the same would be possible by estimating the respective fraction of this unit.

Prior to its use the tacheometer must be adjusted in such a way that the length of that part of the staff, by which in the image field the two double images are displaced relatively to each other, multiplied by a round figure (e. g., 100) indicates the distance. Thereby the distances *s*¹ and *s*² of the semi-lenses *c*⁴ and *c*⁵ out of their middle position have a certain, definite value and it must be seen to that that plate *d*, appertaining to the semi-lens *c*⁴, is clamped on the fork *b*¹ according to the value *s*¹.

For using the instrument it should be set up in such a way that the vertical axis X-X is in a perpendicular position, and it is necessary to sight at the staff placed parallelly to the horizontal axis Y-Y. As a rule, the distance apart of the two double images will then not be equal to a whole multiple of the image of the unit of the graduation of the staff, i. e., two divisions of the staff will not coincide with each other. In this case one diminishes the displacement *s*² of the semi-lens *c*⁵ from its middle position by rotating the appertaining plate *d* with the aid of the milled head *d*³ until the distance of the double images is equal to a whole multiple, ascertains by the above multiplication the distance corresponding to this new displacement and adds to this distance that additional distance, resulting from the adjustment of the index *b*² relatively to the drum *e*¹. Thereby that curve *e*³ holds good which passes through the point of intersection of the index with the circular line *e*², corresponding to the distance ascertained. When measuring, the semi-lenses *c*⁴ and *c*⁵, owing to the sliding of the balls *c*⁸ on the plates *d*, always undergo such a displacement that the distances read off are the horizontal distances.

The second constructional example shown in Fig. 3 serves for operating with one and the same section of the staff. It differs from that of the first constructional example by the feature that the semi-lens *c*⁴ is fixed on

the telescope casing c in such a way as to occupy the middle position mentioned in the description of the first example. The automatic reduction of the distance only takes place yet by means of a single plate d , appertaining to the semi-lens c^5 . The arrangement made in the first example for the purpose of the exact reading of the fractions of the unit of the graduation of the staff 10 has been dispensed with. A novel feature is represented by a scale b^3 numbered according to distances which is fixed on the fork b^1 coaxially with the shaft d^2 and connects with an index d^3 rigidly connected to the milled head d^8 .

When using the instrument it is necessary to adjust by rotating the plate d by means of the milled head d^8 such a distance between the two double images that the one 20 end of the one double image coincides with the other end of the other double image, whereupon the reduced distance of the staff can be read off on the scale b^3 .

The third constructional example shown 25 in Figs. 4 and 5 is destined to operate with an invariable measuring angle, and therefore with different sections of the staff. As shown in the second example, the semi-lens c^4 is fixed on the telescope casing but in 30 such a way that it is displaced out of its middle position by the amount s^1 . For reducing purposes it is only the semi-lens c^5 than can be adjusted. For reducing the distance serves in this case a bevel wheel f , 35 which is supported on an arm c^9 , fixed on the casing of the telescope c , rotatably about an axis parallel to the objective axis c^1 . This bevel wheel engages on the one hand in another bevel wheel b^8 fixed on the fork 40 b^1 , on the other hand it carries a pivot f^1 engaging in the slit of a slide c^{10} rigidly connected to the pivot c^7 . Thereby the distance of the pivot f^1 from the axis of rotation of the bevel wheel f is so chosen as 45 to be equal to the total of the invariable displacement s^1 of the semi-lens c^4 and that displacement s^2 of the semi-lens c^5 out of the appertaining middle position each, which appertains to the horizontal position 50 of the telescope.

During the use of the tacheometer the bevel wheel f , adjustment being made to an angle of elevation deviating from zero, rolls over the bevel wheel b^8 , whereby it experiences such a rotation about its own axis of rotation that in each case the angular amount of the rotation is equal to the corresponding angular amount of the rotation of the telescope about its horizontal axis $Y-Y$. 55 Owing to the engaging of the pivot f^1 in the slide c^{10} the semi-lens c^5 undergoes such a displacement that the distance between the double images is, as required, a measure for the reduced distance.

60 The fourth constructional example shown

in Figs. 6 and 7 is destined to be used with different sections of the staff. The optical outfit is assumed to be the same as that in the above described constructional examples, i. e., for the semi-lenses the arrangement of the second example (vide Fig. 3) is based upon, that the one semi-lens (not shown) assumes its middle position and is fixed on the casing of the telescope c in this position. In order to reduce the distance on 70 the horizontal plane there is supported on the telescope casing a square-rod g displaceable parallelly to the objective axis, which rod carries a slide g^1 in whose slit engages a pivot b^4 . This pivot is fixed on the fork b^1 in such a way that its axis is parallel to the horizontal axis $Y-Y$ and lies with the latter in one and the same horizontal plane. The square-rod g carries a sliding piece g^2 , having a plane surface g^3 , 80 against which is pressed by means of the spring c^0 the ball c^8 of the pivot c^7 rigidly connected to the semi-lens c^5 . The incline of the surface g^3 to the horizontal axis $Y-Y$ and the distance of the pivot b^4 from this axis are so chosen that the displacement, brought about with rotations of the telescope about its horizontal axis, of the square-rod g produces such a displacement 85 of the semi-lens c^5 that the distance between the double image is, as required, a measure for the reduced distance.

I claim:

1. In a reducing tacheometer a telescope rotatably disposed about a horizontal axis, which is perpendicular to the optical axis of the telescope, the telescope comprising an objective and an ocular, two semi-lenses inserted in the path of the rays before the ocular and displaceable parallelly to the said horizontal axis, and means for coupling the semi-lenses and the telescope so as to impart to the semi-lenses a relative displacement as the telescope is rotated about the said horizontal axis, these means comprising at least one plane surface coacting with one of the semi-lenses.

2. In a reducing tacheometer a telescope rotatably disposed about a horizontal axis, which is perpendicular to the optical axis of the telescope, the telescope comprising an objective and an ocular, two semi-lenses inserted in the path of the rays before the ocular and displaceable parallelly to the said horizontal axis, and means for coupling the semi-lenses and the telescope so as to impart to the semi-lenses a relative displacement as the telescope is rotated about the said horizontal axis, these means comprising at least one gearing constructed after the manner of a crank guide and coacting with one of the semi-lenses.

3. In a reducing tacheometer a telescope rotatably disposed about a horizontal axis, which is perpendicular to the optical axis of

the telescope, and about a vertical axis, the telescope comprising an objective and an ocular, two semi-lenses, inserted in the path of the rays before the ocular and displaceable parallelly to the said horizontal axis, and means for coupling the semi-lenses and the telescope so as to impart to the semi-lenses a relative displacement as the telescope is rotated about the said horizontal axis, these means comprising at least one plane surface, which surface is parallel to the said vertical axis and intersects the said horizontal axis at an angle deviating from 90°, this surface coacting with one of the semi-lenses.

4. In a reducing tacheometer a telescope rotatably disposed about a horizontal axis, which is perpendicular to the optical axis of the telescope, the telescope comprising an objective and an ocular, two semi-lenses inserted in the path of the rays before the ocular and displaceable parallelly to the said horizontal axis, means for coupling the semi-lenses and the telescope so as to impart to the semi-lenses a relative displacement as the telescope is rotated about the said horizontal axis, these means comprising at least one plane surface, which surface is parallel to the said vertical axis and intersects the said horizontal axis at an angle deviating from 90°, this surface coacting with one of the semi-lenses.

5. In a reducing tacheometer a telescope rotatably disposed about a horizontal axis, which is perpendicular to the optical axis of the telescope, the telescope comprising an objective and an ocular, two semi-lenses inserted in the path of the rays before the ocular and displaceable parallelly to the said horizontal axis, means for coupling the semi-lenses and the telescope so as to impart to the semi-lenses a relative displacement as the telescope is rotated about the said horizontal axis, these means comprising at least one slide fitted to the telescope in such a way as to take part in rotations about the

said horizontal axis, this slide having a plane surface coacting with one of the semi-lenses, and a gearing constructed after the manner of a crank guide and fitted to the telescope, this gearing being adapted to convert rotations of the telescope about the horizontal axis into displacements of the slide.

6. In a reducing tacheometer a telescope rotatably disposed about a horizontal axis, which is perpendicular to the optical axis of the telescope, the telescope comprising an objective and an ocular, two semi-lenses inserted between the objective and the ocular and displaceable parallelly to the said horizontal axis, the distances of the objective and the semi-lenses from the said horizontal axis and the focal length of the objective being so chosen that a virtual image of the semi-lenses is produced at the locus of the horizontal axis, and means for coupling the semi-lenses and the telescope so as to impart to the semi-lenses a relative displacement as the telescope is rotated about the said horizontal axis, these means comprising at least one plane surface coacting with one of the semi-lenses.

7. In a reducing tacheometer a telescope rotatably disposed about a horizontal axis, which is perpendicular to the optical axis of the telescope, the telescope comprising an objective and an ocular, two semi-lenses inserted in the path of the rays before the ocular and displaceable parallelly to the said horizontal axis, means for coupling the semi-lenses and the telescope so as to impart to the semi-lenses a relative displacement as the telescope is rotated about the said horizontal axis, these means comprising at least one plane surface coacting with one of the semi-lenses, a driving device adapted to impart to one of the semi-lenses a displacement independently of rotations of the telescope, and a scale and an index coacting with each other, the relative position of which is controlled by the said driving device.

ALBERT KÖNIG.
